Primary Examiner — Robin V Webster(74) *Attorney, Agent, or Firm* — Larson & Anderson,
LLC(57) **CLAIM**

The ornamental design for fluid distribution equipment, as shown and described.

DESCRIPTION

FIG. 1 is a perspective view of fluid distribution equipment showing my new design;

FIG. 2 is another perspective view thereof;

FIG. 3 is a top view thereof;

FIG. 4 is an end view thereof;

FIG. 5 is the other end view thereof;

FIG. 6 is a side view thereof; and,

FIG. 7 is the other side view thereof.
